UNITED STATES PATENT OFFICE.

PAUL EDWIN WOOLFOLK, OF WACO, TEXAS.

EGG-TESTING GLOBE.

1,207,354.

Specification of Letters Patent.

Patented Dec. 5, 1916.

Application filed July 7, 1916. Serial No. 107,978.

To all whom it may concern:

Be it known that I, PAUL E. WOOLFOLK, a citizen of the United States, residing at Waco, in the county of McLennan and 5 State of Texas, have invented certain new and useful Improvements in Egg-Testing Globes, of which the following is a specification.

This invention relates to an egg tester, 10 and is designed for use with an ordinary hand lantern.

I am aware of the fact that egg testers have been used in the form of an opaque chimney for a lamp burner the same being 15 provided with a lateral extension having an opening in which the egg is held and through which light passes from the tester, through the egg to the eye of the observer. But devices of this character are usually 20 used in out buildings where incubators are run, or in stores, warehouses and the like, many of which are of frame construction or filled with much inflammable material. The carrying of the ordinary coal oil lamp 25 into these places is dangerous and objectionable, and may in some cases invalidate insurance policies. And so far as is known to me no simple egg testing globe has been devised heretofore that could be quickly applied to and used in connection with the 30 usual type of hand lantern.

My invention therefore relates to a testing device which can be substituted for the usual glass globe of the ordinary hand lantern, thereby converting said lantern into a 35 candling or testing device.

In the accompanying drawings: Figure 1 is a vertical section through my globe. Fig. 2 is a face view of a lens.

40 In constructing my device I employ a globe 1 having the shape of the usual lantern globe, and this may be of any suitable material, either glass, earthenware or metal. When made of glass the outer surface is 45 coated as at 2, this coating being of any suitable opaque substance, and preferably black.

When of metal or earthenware the outer surface is also preferably blackened, as by a black enamel or japanning. Whatever the material of the globe may be the inner surface has a coat 3 of whiting, either white enamel or other suitable white coating. On one side the globe carries an integral lateral extension 4 in which is fitted a corrugated glass 5. Adjacent the top the globe has a 50 bead 6 and at the bottom a flange 7 so that it may be secured in the lantern frame in the usual manner, simply replacing the usual glass globe. The source of light is not however material, and when electric light is 55 available the globe may be set on any suitable flat surface and an electric light bulb permitted to hang therein. This forms therefore a simple, cheap and very safe egg testing device. By giving the inner face of 60 the globe a white coating the amount of light reflected through the egg is increased and the use of the glass 5 also tends to increase the illumination of the interior of the egg, as well as diffusing the light and preventing the eye of the observer becoming confused after a short time as is the case 65 where the light is directly visible while the egg is being placed in and removed from position. The visibility of the source of 70 light during the testing operation will, after a short time, cause "spots" to appear before the eye, which makes it practically impossible to accurately determine the condition 75 of the egg itself.

80 What I claim is:—

An egg testing globe having a lateral extension, a piece of corrugated glass in said extension, a white opaque coating on the interior of the globe, a bead near the top of 85 the globe and a flange at the bottom of the globe, thereby adapting the globe to be inserted in the frame of an ordinary hand lantern.

80 In testimony whereof I affix my signature. 90

PAUL EDWIN WOOLFOLK.
